No. 634,024

Patented Oct. 3, 1899.

A. PATERSON.
PRINTER'S FURNITURE.

(Application filed Jan. 23, 1899.)

(No Model.)

UNITED STATES PATENT OFFICE.

ALEXANDER PATERSON, OF LONDON, ENGLAND.

PRINTER'S FURNITURE.

SPECIFICATION forming part of Letters Patent No. 634,024, dated October 3, 1899.

Application filed January 23, 1899. Serial No. 703,208. (No model.)

To all whom it may concern:

Be it known that I, ALEXANDER PATERSON, a subject of the Queen of Great Britain, residing at London, in the county of Middlesex, England, have invented certain new and useful Improvements in Printers' Furniture, of which the following is a full and complete specification, such as will enable those skilled in the art to which it appertains to make and use the same.

This invention relates to improvements in printers' furniture, and has more particular reference to a locket or corner-piece for clamps used in printers' forms in filling up spaces remaining therein where no printed matter appears.

The object of my invention is to eliminate the present methods used to obtain the end in view, which consists in filling up blank spaces with solid metal or wooden furniture.

The invention is fully disclosed in the following specification, of which the accompanying drawings form a part, in which like letters of reference refer to like parts in the several views, and in which—

Figure 1 is a plan view of a printer's form provided interiorly with my improved lockets or corner-pieces, between which are securely bound clamps; Fig. 2, an end view thereof. Fig. 3 is a perspective end view of one of my lockets or corner-pieces shown in Fig. 1. Fig. 4 is a plan view of parts of two clamps in connection with a locket or corner-piece for larger clamps than are shown in Fig. 1. Fig. 5 is a plan view of parts of two clamps in connection with a locket or corner-piece of the same size as shown in Fig. 3, but which is built up to fit larger clamps; and Fig. 6 represents two lockets and an interposed clamp joined together and supported by side clamps similar to Fig. 4.

Referring more particularly to the drawings, A is a corner-piece or locket formed according to my invention, and consists of a block, preferably of metal or other unyielding material, and is angular in shape, forming two parallel oppositely-extending members A' and A'', which are separated by longitudinal angular grooves B and C.

When filling up spaces in which no printing appears, the lockets A are placed in the corners of the forms E, as shown in Fig. 1,

and the clamps D are fitted between the lockets, filling out the unoccupied space in the forms. The lockets A are made of different sizes, corresponding to the different sizes of the clamps D, which in turn correspond to the different width and depth of the spaces to be filled.

In Fig. 1 I have shown a single clamp D' double the width of the clamp D, and the purpose of the clamp D' is to divide a column or space to brace or strengthen the same.

In Fig. 4 is shown a modified locket F for use with larger clamps than those shown at D in Fig. 1. The upper member F' thereof is enlarged with relation to the corresponding member A' of the locket A in Figs. 1 and 3, and the lower member A'' thereof is enlarged with relation to the member of the locket A. In lieu of the construction employed in Fig. 4 that shown in Fig. 5 may be used.

In Fig. 5 is shown a modified corner-piece, comprising a locket H, the lower member A'' of which is formed as usual, as is the upper member A'; but the latter is built up by the addition thereto of pica quads or blanks K, thus obviating the necessity of having in stock for use more than the smallest size of locket.

The clamps L (shown broken off in Fig. 5) are by the use of the pica quads K of larger size than the clamps D.

In Fig. 6 is shown a combined locket and clamp M for use in producing blank spaces of a similar width or thickness in the midst of printed matter. These devices M are useful in producing blank pages in bookwork. The combined locket and clamp M is made of such operative dimensions as it is desired the resultant blank space to have and is mounted upon side clamps N of the ordinary construction already described.

It is evident that many changes may be made in the construction and arrangement of my device, and I claim all such as come within the spirit of my invention.

Having fully described my invention, I claim as new and desire to secure by Letters Patent—

1. In printers' furniture, an angular corner-piece consisting of a body portion provided with oppositely-extending angular projections, projecting therefrom adjacent the

diagonally opposite corners of said body portion, substantially as shown and described.

2. In printers' furniture, an angular locket or corner-piece consisting of a block provided with parallel and oppositely-extending angular projections, whereby grooves are formed adapted to fit the end portion of clamps or blocks in connection with which they are used, substantially as shown and described.

In testimony that I claim the foregoing as my invention I have signed my name, in presence of the subscribing witnesses, this 10th day of December, 1898.

ALEXANDER PATERSON.

Witnesses:

ALEXANDER MENZIES,
JAMES MCBRYDE.
